UNITED STATES PATENT OFFICE

91,422

DESIGN FOR A TOY

Davis W. Fisher, Brownfield, Tex.

Application November 21, 1933. Serial No. 49,815

Term of patent 3½ years

To all whom it may concern:

Be it known that I, DAVIS W. FISHER, a citizen of the United States, residing at Brownfield, in the county of Terry and State of Texas, have invented a new, original, and ornamental Design for a Toy, of which the following is a specification, reference being had to the accompanying drawing, forming part thereof.

I claim:—

The ornamental design for a toy as shown.

DAVIS W. FISHER.
